UNITED STATES PATENT OFFICE.

EDWARD KLEMM, OF BOONTON, NEW JERSEY.

METHOD OF AND DEVICE FOR FINISHING THE FOOT PORTIONS OF STOCKINGS.

Application filed April 11, 1927. Serial No. 182,679.

My invention relates to a new and improved method of and device for finishing the foot portion of a stocking.

One of the objects of my invention is to provide a device whereby the foot portion of a stocking can be completed without injuring the sheer fabric of the body or leg portion of the stocking.

Another object of my invention is to provide a device for maintaining the proper tension upon a stocking while the foot portion thereof is being knit or completed, in which the maximum holding effect will be exerted upon the reinforced edge portions of the stocking while the intermediate and more delicate portions of the stocking will be frictionally held without injury thereto.

Another object of my invention is to provide a hookless holding device for the intermediate body portion of a fashioned stocking, to assist in keeping this under proper tension, while the foot portion of the stocking is being knit or completed.

Other objects of my invention will be set forth in the following description and drawings which illustrate a preferred embodiment of my invention, it being understood that the above general statement of the objects of my invention is intended merely to generally explain the same and not to limit it in any manner.

Fig. 1 is a top view of the improved holding device.

Fig. 2 is a front view of the device shown in Fig. 1.

Fig. 3 is a side view of the before mentioned device.

Fig. 4 is a diagrammatic view showing the device in use.

In making a full fashioned stocking, it is necessary to first knit the body or leg portion thereof and to then knit the foot portion of the stocking in a second machine which is ordinarily called the "footer."

In previously known devices, it was necessary to hold the relatively thin and delicate intermediate portion of the leg of the stocking by means of hooks while the necessary tension was exerted in order to knit the foot

portion of the stocking. This tension caused runs to form in the thin leg portion of the stocking, directly adjacent the holding hooks, so that a very large percentage of such stockings which were knit in a plant were found to be defective because "runs" formed therein and these runs had to be repaired before the stockings could be sent out.

According to my invention, no hooks are used for holding the stocking in the footer save at the reinforced edge portions of the stocking and the more delicate intermediate portion of the leg of the stocking is held without the formation of runs by means of a suitable frictional device.

As shown in Fig. 4, the stocking is knit in the ordinary machine so that it has outer reinforced heel and sole portions 1. The intermediate body portion 2 of the leg of the stocking is ordinarily not reinforced and it is therefore much more delicate than the outer portions 1.

The body portion 2 of the stocking is now removed from the needles of the ordinary machine and the meshes thereof are placed upon the needles N of the footer. The intermediate leg portion 2 of the stocking is passed between a bar 3 made of any suitable rigid material, such as steel and the like, and it is held in place by means of spring clips 4 and 5 which exert a frictional hold upon the instep portion of the stocking. The bar 3 is also provided at the ends thereof with hooks 6 and 7 which are caused to enter the reinforced portions 1 of the stocking. An ordinary strap 8 has one end thereof suitably connected to the central portion of the bar 3 and this strap 8 is connected to any suitable tension device such as a shaft or pulley 10 which is suitably turned by the well known means in order to exert a proper pull upon the bar 3.

The hooks 6 and 7 are connected to the outer ends of the bar 3 by means of screws 9. As shown in Fig. 3, the spring clips 4 and 5 are between the hooks and the bar 3 but my invention is not limited to this construction and if desired, the hooks could be placed intermediate the bar 3 and the spring clips 4 and 5.

The spring clips 4 and 5 exert a sufficient frictional hold upon the instep portion of the stocking to maintain it in the flat condition shown in Fig. 4 so as to enable the foot 5 portion of the stocking to be properly completed by the needles N.

The spring clips 4 and 5 serve to clip the intermediate instep portion 2 of the stocking not only at their adjacent or inner ends 10 but also at their opposite ends adjacent the hooks, so that the pull on the instep portion 2 is not concentrated along a single and relatively median line. The clips could also be designed so as to uniformly grip the instep 15 portion 2 along the entire width thereof so as to disperse the tension effect as much as possible.

Even if the clips subject the portion of the stocking which they clip to the same tension 20 which is produced by the hooks 6 and 7, runs are prevented because the tension effect produced by the clips is distributed along a wide lateral line. Hence the tension produced by said spring clips upon the meshes of the 25 stocking which they engage is less than the tension produced upon the meshes of the stocking directly adjacent the hooks 6 and 7.

Hence, while the foot portion of the stocking is being knitted no portion of the thin delicate fabric is subjected to the tearing action 30 of a hook and the knitting can be accomplished more reliably and in a more uniform manner because the instep portion is being subjected to tension along a substantial portion thereof and in particular it is being subjected to tension along lines spaced from the median line thereof. The spring clips 4 and 35 5 could be extended, if desired, so as to extend across the entire width of the foot member.

It will be noted, however, that the clips 4 and 5 preferably do not extend over the central part of the bar 3 so that the central part of the instep portion of the stocking is relatively free. Hence, the tension exerted by 45 the strap 8 is confined to the reinforced edge portions of the stocking, and to the edge portions of the sheer instep of the stocking. Experience has shown that this causes the stocking to be finished in a more uniform 50 manner and with little or no danger of the formation of "runs".

Since the hooks 6 and 7 positively engage the reinforced edge portions of the foot member, the direct pull and hence the direct tension 55 upon said reinforced edge portions is greater than the direct tension exerted upon the edge portions of the instep, because the hold of the hooks 6 and 7 is positive and of 60 greater force than the frictional hold supplied by the clips 4 and 5.

I have shown a preferred embodiment of my invention but it is clear that numerous changes and omissions could be made without 65 departing from its spirit.

I claim:

1. In the art of forming the foot member of a fashioned stocking, that step in the art which consists in maintaining the edge portions of the said foot member under direct 70 tension while the knitting thereof is being performed, while maintaining the central portion of the said foot member substantially free from any direct tension.

2. In the art of forming the foot member 75 of a fashioned stocking having a reinforced heel and sole and a relatively sheer instep, that step which consists in subjecting the reinforced portion of the foot member and the edge portions of the instep to direct tension 80 while the knitting of the foot member is being performed while maintaining the central portion of the instep relatively free from direct tension.

3. In the art of forming the foot member 85 of a fashioned stocking, that step in the art which consists in subjecting the reinforced edge portions of the foot member to tension while the knitting of the foot member is being performed, and subjecting the relatively 90 sheer inner portion of the foot member to less tension while said knitting is being performed.

4. In combination with a footer machine, a tension bar having hooks at the ends thereof adapted to engage meshes of a stocking so as to subject vertical rows of said meshes adjacent said hooks to tension, friction clip means connected to said tension bar and located intermediate the ends thereof, said friction clip means being adapted to engage other meshes of the stocking, each of said hooks being adapted to subject a vertical row of meshes adjacent thereto, to a tension which is greater than is caused by said friction clip means upon the individual rows of meshes subjected to tension thereby. 95

5. In combination with a footer machine, a tension bar having hooks at the ends thereof adapted to engage meshes of a stocking so as to subject vertical rows of said meshes adjacent said hooks to tension, friction clip means connected to said tension bar and located intermediate the ends thereof, said friction clip means being adapted to engage other meshes 110 of the stocking, each of said hooks being adapted to subject a vertical row of meshes adjacent thereto, to a tension which is greater than is caused by said friction clip means upon the individual rows of meshes subjected to tension thereby and the inner ends of said friction clip means being spaced from each other. 115

6. In a footer attachment for knitting machine, a base member, hooks spaced apart on said base member and a yieldingly fabric engaging clamp device intermediate said hooks. 120

7. In a footer attachment for knitting machines hook members for engaging the heel tabs, a clamp having yielding means for en- 130

gaging the stocking fabric intermediate the heel tabs and means for moving said hook members and said clamp in unison.

8. In a footer attachment for knitting machines means for engaging the heel tabs and a clamp device including yielding means for engaging the stocking fabric intermediate the tabs.

9. In a knitting machine attachment, a base plate having heel tab engaging members spaced apart and a clamping member including resilient means intermediate said heel tab engaging members for yieldingly engaging the stocking fabric. 10

In testimony whereof I affix my signature.
EDWARD KLEMM.
